STOKER FIRED FURNACE WITH RECIPRO-
CABLE GRATE AND DRAFT CONTROL

George C. Molotszak, Coaldale, Pa.

Application November 22, 1948, Serial No. 61,406

3 Claims. (Cl. 110—38)

1

This invention relates to furnaces which are fired with solid fuel by means of a mechanical stoker, and which have a grate that is reciprocable to deliver ashes out of the fuel bed into an ash pit.

In furnaces of the above kind, the stoker and grate are usually operated by thermostatically controlled mechanisms so that they are simultaneously thrown into operation when more heat is demanded of the furnace and out of operation when the heat produced by the furnace meets a predetermined demand.

An object of the present invention is to provide a furnace of the above kind having an ash pit chamber, an air inlet chamber behind the ash pit chamber, a front firebox over the ash pit chamber, a rear combustion chamber over the air inlet chamber, a transverse bridge wall between the firebox and the combustion chamber, an outlet flue for products of combustion depending within the combustion chamber to a point below the top of the bridge wall, a damper positionable to either close direct communication between the air inlet chamber and the ash pit chamber and simultaneously open direct communication between said air inlet chamber and the combustion chamber or to open direct communication between the air inlet chamber and the ash pit chamber and simultaneously close direct communication between said air inlet chamber and the combustion chamber. In this way, an up-draft of air may be had from the air inlet chamber through the fire bed when more heat is demanded and air may be supplied from the air inlet chamber directly and only to the combustion chamber when the heat produced by the furnace meets the predetermined demand.

Another object is to provide means for positioning the damper to close communication between the air inlet chamber and the ash pit chamber when the stoker and grate operating unit is inoperative and the heat produced by the furnace meets the predetermined demand, and for automatically opening communication between said air inlet chamber and the ash pit chamber when the stoker and grate operating unit are rendered operative and more heat is demanded. Preferably, the damper is operatively connected to a centrifugal governor driven by the driving motor of the operating unit.

The exact nature of the present invention, as well as other objects and features thereof, will become apparent from the following description when considered in connection with the accompanying drawings, in which:

2

Figure 1 is a view partly in vertical section and partly in side elevation, of a furnace embodying the present invention;

Figure 2 is a horizontal section taken on the line 2—2 of Figure 1;

Figure 3 is a fragmentary horizontal section taken on the line 3—3 of Figure 1, with parts omitted;

Figure 4 is a fragmentary elevational view 10 showing the driving connection between the motor of the operating unit and one of the crank discs of the latter.

Referring in detail to the drawings, I have shown a water heating furnace or boiler B, the 15 body of which has water jacketed top, side, front and rear walls, the front wall being provided with a fuel feed opening 5. The interior of the furnace body is divided by a transverse water bridge wall 6 into a front firebox 7 and a rear combustion chamber 8, and the front wall is connected to the bridge wall by rearwardly inclined water tubes 9 and 10, respectively arranged directly above and directly below the fuel feed opening 5. The body of the furnace is mounted on a base 11 which is divided by a transverse partition 12 into a front ash pit chamber 13 beneath the firebox and a rear air inlet chamber 14 beneath the combustion chamber. The base 11 has a top opening 15 providing for communication 20 between the combustion chamber 8 and the air inlet chamber 14, and the partition 12 has an opening 16 providing for communication between the ash pit chamber 13 and the air inlet chamber 14. The side walls of the base have louvered 25 openings as at 17 for the admission of outside air to the chamber 14. A damper 18 is hinged at 19 to swing from the full line position wherein the same closes the opening 16 to the dotted line position wherein it closes the opening 15, and vice versa.

A reciprocable grate 20 is mounted at a rearward inclination between the firebox 7 and the ash pit chamber 13, and an operating rod 21 is fixed at one end to the grate and projects outwardly through the front of the furnace. A segment gear 22 is fixed to the shaft of damper 18 and is meshed by a rack bar 23 carried by the rear end of a second operating rod 24 that also projects through the front of the furnace.

A mechanical stoker 25 is associated with the furnace to feed solid fuel through the feed opening onto the grate. This stoker may be of the type shown in my U. S. Patent No. 2,377,357 dated 50 June 5, 1945, the same embodying a reciprocating

ing feeder plate which is provided with an operating rod 26.

The operating rods 21, 24 and 26 are operatively connected to a common driving unit or mechanism employing an electric motor 27 and arranged within a casing 28. The grate operating rod 21 is extended into the casing 28 and terminates in a transverse member 29 which has an elongated slot 30 into which projects a lateral crank pin 31 of a combined crank and pulley wheel 32 suitably journaled within the casing. The operating rod 26 includes a section 33 attached to the stoker feeder plate, and a section 34 rigidly connected at 35 to the section 33 and projecting rearwardly into the casing 28. The section 34 terminates in a transverse member 36 which has an elongated slot 37 into which projects a lateral crank pin 38 of a second combined pulley and crank wheel 39 which is suitably journaled within the casing above the wheel 32. An endless transmission belt 40 passes around the wheels 32 and 39, and the drive shaft 41 of motor 27 is operatively connected to wheel 39 by a worm gearing 42 as shown in Figure 4.

Associated with the drive shaft 41 of motor 27 is a centrifugal governor 43 which is operatively connected at 44 to the damper operating rod 24. The casing 28 is adapted to be filled with a lubricant, and escape of the lubricant from said casing about the rods 21 and 24 and the rod section 34 is prevented by seals 45 of the bellows type. A thermostatic switch 46, subjected to the temperature of the water in the water space of the furnace, may control the operation of the motor 27.

Vertical flues 47 project through the top of the furnace and depend within the combustion chamber 8 to a point below the top of the bridge wall 6, said flues being adapted to carry off the products of combustion and having the portions thereof within the combustion chamber water jacketed as at 48.

When the heat produced by the furnace meets a predetermined demand, the motor 27 is inoperative and the parts are positioned as shown, the main supply of air for promoting combustion being allowed to flow directly from the air inlet chamber 14 into the combustion chamber 8 through opening 15 and being prevented from flowing into the ash pit chamber 13 by damper 18. When more heat is demanded, the motor 27 is thrown into operation so as to actuate the stoker, reciprocate the grate, and swing the damper 18 to the dotted line position. In this way, ashes are shaken from the fire bed into the ash pit chamber, fuel is fed on to the grate by the stoker, and an updraft of air is provided through the fire bed so as to effectively increase the heat produced by the furnace until it meets a predetermined demand. The thermostatic switch then throws the motor 27 out of operation so that shaking of the grate and feeding of the fuel is discontinued, and damper 18 is returned to the full line position wherein substantial draft through the fire bed is discontinued. Some air may be admitted to the ash pit chamber at all times through a damper 49 provided in the door 50 of the ash pit chamber. Obviously, when the shaft 41 is driven, the weights of governor 43 move outwardly and cause its springs to flex and thereby move the rod 24 to swing damper 18 to the dotted line position. On the other hand, when shaft 41 discontinues rotation, the springs of the governor straighten and move

the rod 24 to return the damper 18 to the full line position.

From the foregoing description, it is believed that the construction, operation and advantages of the present invention will be readily understood and appreciated by those skilled in the art. Modifications and changes in details of construction are contemplated, such as fairly fall within the spirit and scope of the invention as claimed.

Having described the invention, what is claimed as new is:

1. A water heating furnace having walls and a grate defining a front ash pit chamber, an air inlet chamber directly behind the ash pit chamber, a firebox over the ash pit chamber, and a combustion chamber communicating with and located behind the firebox and over the air inlet chamber; one of said walls comprising a transverse bridge wall between the firebox and the combustion chamber, another of said walls being between the air inlet and combustion chambers and having an opening affording communication between said air inlet and combustion chambers when open, still another of said walls being between the ash pit and air inlet chambers and having an opening affording communication between said ash pit and air inlet chambers when open, a flue for the escape of products of combustion depending within the combustion chamber to a point below the top of the bridge wall, the grate being between the firebox and the ash pit chamber, and a damper mounted in the air inlet chamber and positionable to open either of said openings and simultaneously close the other to selectively establish direct communication between the air inlet chamber and the ash pit chamber or between the air inlet chamber and the combustion chamber.
2. A water heating furnace having walls and a grate defining a front ash pit chamber, an air inlet chamber directly behind the ash pit chamber, a firebox over the ash pit chamber, and a combustion chamber communicating with and located behind the firebox and over the air inlet chamber; one of said walls comprising a transverse bridge wall between the firebox and the combustion chamber, another of said walls being between the air inlet and combustion chambers and having an opening affording communication between said air inlet and combustion chambers when open, still another of said walls being between the ash pit and air inlet chambers and having an opening affording communication between said ash pit and air inlet chambers when open, a flue for the escape of products of combustion depending within the combustion chamber to a point below the top of the bridge wall, the grate being between the firebox and the ash pit chamber, and a damper mounted in the air inlet chamber and positionable to open either of said openings and simultaneously close the other to selectively establish direct communication between the air inlet chamber and the ash pit chamber or between the air inlet chamber and the combustion chamber.
3. A water heating furnace having walls and a grate defining a front ash pit chamber, an air inlet chamber directly behind the ash pit chamber, a firebox over the ash pit chamber, and a combustion chamber communicating with and located behind the firebox and over the air inlet chamber; one of said walls comprising a transverse bridge wall between the firebox and the combustion chamber, another of said walls being between the air inlet and combustion chambers and having an opening affording communication between said air inlet and combustion chambers when open, still another of said walls being between the ash pit and air inlet chambers and having an opening affording communication between said ash pit and air inlet chambers when open, a flue for the escape of products of combustion depending within the combustion chamber to a point below the top of the bridge wall, the grate being between the firebox and the ash pit chamber, and a damper mounted in the air inlet chamber and positionable to open either of said openings and simultaneously close the other to selectively establish direct communication between the air inlet chamber and the ash pit chamber or between the air inlet chamber and the combustion chamber, and a motor driven centrifugal governor operatively connected to the damper for positioning the latter so as to close the opening in the wall between the air inlet and ash pit chambers when the driving motor of said governor is rendered inoperative and for positioning the damper so as to close the opening in the wall between the air inlet and combustion chambers when said driving motor is rendered operative.

3. A water heating furnace having walls and a grate defining a front ash pit chamber, an air inlet chamber directly behind the ash pit chamber, a firebox over the ash pit chamber, and a combustion chamber communicating with and located behind the firebox and over the air inlet chamber; one of said walls comprising a transverse bridge wall between the firebox and the combustion chamber, another of said walls being between the air inlet and combustion chambers and having an opening affording communication between said air inlet and combustion chambers when open, still another of said walls being between the ash pit and air inlet chambers and having an opening affording communication between said ash pit and air inlet chambers when open, a flue for the escape of products of combustion depending within the combustion chamber to a point below the top of the bridge wall, the grate being between the firebox and the ash pit chamber, and a damper positionable to open either of said openings and simultaneously close the other to selectively establish direct communication between the air inlet chamber and the ash pit chamber or between the air inlet chamber and the combustion chamber, said grate be-
